UNITED STATES PATENT OFFICE.

EMMA E. MYERS, OF PITTSBURG, PENNSYLVANIA.

DESIGN FOR A WASTE-PIPE CLEANER.

SPECIFICATION forming part of Design No. 32,189, dated February 6, 1900.

Application filed December 7, 1899. Serial No. 739,583. Term of patent 7 years.

To all whom it may concern:

Be it known that I, EMMA E. MYERS, a citizen of the United States of America, residing at Pittsburg, in the county of Allegheny and State of Pennsylvania, have invented a certain new and useful Design for a Waste-Pipe Cleaner, of which the following is a specification, reference being had therein to the accompanying drawing.

This invention relates to certain new and novel designs in waste-pipe cleaners.

The invention consists in the novel shape and general outline of the tool to be herein-after more particularly described.

In describing the invention in detail reference is had to the accompanying drawing, forming a part of this specification, wherein like numerals of reference indicate like parts and which drawing represents a perspective view of my new design of waste-pipe cleaner.

The reference-numeral 1 represents a stem

portion, which is circular in cross-section and carries at its upper extremity an oblong loop 2, having parallel sides and rounded ends, and at its lower extremity a diamond-shaped 25 point 3. Extending upwardly near said diamond-shaped point is arranged a barb 4, which projects outwardly at an incline to the stem 1.

It will be noted that this design is symmetrical and presents a pleasing appearance to 30 the eye.

Having clearly described my design, what I claim as new, and desire to secure by Letters Patent, is—

The design for a waste-pipe cleaner, substantially as herein shown and described.

In testimony whereof I affix my signature in the presence of two witnesses,

EMMA E. MYERS.

Witnesses:

JOHN NOLAND,
E. W. ARTHUR.
